UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

THROTTLE VALVE FOR ROCK DRILLS.

1,407,590.

Specification of Letters Patent. Patented Feb. 21, 1922.

Application filed July 17, 1920. Serial No. 397,022.

To all whom it may concern:

Be it known that I, FRED M. SLATER, a citizen of the United States, residing at Easton, in the county of Northampton and 5 State of Pennsylvania, have invented certain new and useful Improvements in Throttle Valves for Rock Drills, of which the following is a specification.

This invention relates to throttle valves 10 for controlling the supply of motive fluid to the percussive and feeding elements of a fluid operated rock drill of the hammer type, the invention being shown applied to a stope drill, for illustrative purposes.

15 The primary objects of the invention are to enable the operator to have more complete control over his machine and secure a throttle valve having a plurality of different rotative positions for carrying out a cycle 20 of operations adapted to conform to the conditions of the work.

Throttle valves have been devised having several different positions of rotation for accomplishing various objects, but I have 25 devised a throttle valve adapted to be operated to carry out a cycle including at least six different positions to meet the requirements of the work. One of the principal 30 features of the invention resides in the fact that I introduce a position in the cycle which may be termed an "intermediate" position, occurring after the hammer feed has just started with the air feed fully open and the bleeder from the air feed open. In the previous 35 position of the valve, the object has been to admit some air to the air feed and let out a portion of it so as to produce a pressure less than the line pressure and have the hammer start on light air feed. This 40 has been called the "lazy" position or side of the machine. The "intermediate" position of the valve which follows the "lazy" position is such that the water supply is just opening, the hammer supply is about one half or three 45 fourths full on, the oil supply is off and the air feed and air feed bleeder are full on. This is substantially the same position as the "lazy" position but the hammer is 50 stronger to increase the blow and in accordance with this invention the operator is enabled to come to this "intermediate" position by continuing to turn the throttle in the same direction.

Another important feature of the invention 55 consists of a position of the valve which

may be reached in the cycle after the so called "full on" position. In running full on, the supply to the percussive and feeding elements is fully open but the bleeder from the air feed is closed. My valve however, is so 60 constructed that the air feed may be reduced without reducing the hammer and this is accomplished by opening the air feed bleeder and reducing the pressure in the air feed without slowing up the tool. This position 65 may be said to be substantially the reverse of the "lazy" position. Furthermore, in accordance with my construction I can obtain other positions of the valve and control the supply to the hammer with light air 70 feed so that the tool may be kept from crowding into soft ground.

I am enabled to accomplish some of the objects of my invention by providing a two part throttle valve having a lost motion connection between the parts, for distributing motive fluid to both the percussive and feeding elements of the tool, there being ports and passages in each part of the throttle co-operating with ports and passages leading to 80 the percussive and feeding elements for carrying out the cycle of operations hereinafter to be described and claimed.

My improved throttle valve preferably consists of a main plug portion containing 85 motive fluid supply ports cooperating with ports leading to the percussive and feeding elements, and a second plug portion containing a port open at all times to the atmosphere and capable of being moved into and out 90 of communication with a port leading from the feeding element. A lost motion connection is preferably provided between the said two plug portions of the valve, whereby provision is afforded for varying the amount 95 of motive fluid escaping from the feeding element to the atmosphere without changing the supply of motive fluid to the percussive and feeding elements and by this means the force exerted by the feeding element is 100 varied while maintaining any desired supply of motive fluid to the percussive and feeding elements.

Further objects of the invention will 105 hereinafter appear and the invention is illustrated in the accompanying drawings in one of its preferred forms, in which

Figure 1 is a side elevation partly in longitudinal section of a stope drill embodying the invention,

Figure 2 is an enlarged detail view of the throttle valve partly in longitudinal section,

Figure 3 is a detail end view of the valve partly in section looking at the end to which the handle is adapted to be attached,

Figure 4 is a detail perspective view of the two parts or portions of the plug valve, and

10 Figures 5 to 10 inclusive are diagrammatic views taken through the valve on the lines 5^a, 5^b, 5^c, 5^d, 5^e and 5^f to indicate different positions of the valve throughout the cycle of operations.

15 Referring to the drawings, the rock drill is provided with the cylinder A of any suitable or usual form in drills of the hammer type, and any suitable means (not shown) may be provided for imparting rotation to

20 the drill steel B. The hammer cylinder and its operative parts for imparting impact blows of the hammer to the drill steel form the percussive element of the tool.

The air feed element comprises in this 25 instance, the usual air feed cylinder C having the piston rod D provided with the rock engaging point E. Fluid pressure is admitted to the percussive and feeding elements through the inlet F and the throttle 30 valve forming the subject matter of the present invention distributes the motive fluid to both of said elements. Cleansing water for the machine is admitted at the inlet G and a spring pressed water inlet 35 valve H of any suitable or desirable construction is preferably provided and adapted to be controlled and operated by the rotative movement of the throttle valve. The water passes through the passage J to the 40 drill steel in the usual manner.

In accordance with this invention the throttle valve preferably comprises two portions, a main plug portion K having a hollow bore indicated by the dotted lines L 45 in Figure 2 and provided with ports leading to the percussive and feeding elements, and a second plug portion O having a passage P open at all times to the atmosphere and capable of being moved into and out 50 of communication with a port Q shown in Figures 3 and 5 to 10 leading to the feeding element. As shown the passage P communicates with transverse ports R and S in the second plug portion of the valve which 55 may be turned into and out of communication with the air feed bleeder port Q. The second plug portion O may also be provided with a handle T and a lost motion connection is provided between the two portions of the plug valve, in this instance the main portion K being cut away at U and provided with the flat shoulder V, while the second plug portion O is cut away at W and provided with the angular shoulder or cam 60 surfaces X and Y so that when the two

plug portions are placed together end to end, the cam surfaces X and Y of the second plug portion O may rock on the flat surface forming a shoulder V of the main plug portion K. By means of this construction the second plug portion O having the handle T may be moved through a given angle without moving the main plug portion K.

The main plug portion K is provided with 75 a groove g in its periphery communicating with the interior of the valve and adapted to cooperate with the air feed supply port h shown in Figures 3 and 5 to 10 for supplying air to the air feed element of the machine.

An oil port j is provided in the main plug portion K adapted to cooperate with the oil port h shown in Figures 5 to 10. The main plug portion K is also provided with the 80 main supply port o cooperating with the supply port p shown in Figures 3 and 5 to 10 for distributing motive fluid to the percussive and rotating elements of the machine.

The main plug portion K may also be provided with a cam surface q on which the plunger r of the water valve H bears for operating the water valve in accordance with the movements of the throttle.

In the operation of the device and referring more particularly to Figures 5 to 10 inclusive, it is to be understood that each set of figures from 5 to 10 indicates a position of the valve in the cycle of operations. Each figure includes diagrams on six transverse sections of the valve lettered a, b, c, d, e, and f corresponding to the section lines 5^a, 5^b, 5^c, 5^d, 5^e and 5^f.

In position 1 indicated in Figure 5, all 105 the ports and passages are shut off except the air feed bleeder port Q which is open and prevents any pressure remaining, existing or accumulating in the air feed.

In position 2 indicated in Figure 6, the 110 second plug portion O of the valve has been rotated through a small angle clockwise until the cam surface Y bears upon the cam surface V and then the two plug portions have been rotated together a sufficient 115 distance to slightly open the air feed port h and admit sufficient pressure to raise the tool to its work. The bleeder Q has been closed by the rotation of the second plug portion O. All the other ports and 120 passages have remained closed.

In the third position indicated in Figure 7, the water and oil supply are still closed, but the hammer feed through the ports o and p is just starting, the air feed through 125 the port h is partly open and the air feed bleeder Q is again open. In this position a certain amount of fluid pressure is admitted to the hammer cylinder and a certain amount of pressure is exhausted from the 130

air feed cylinder in order to produce a pressure less than the line pressure and permit the hammer to start on light air feed. This is the so called "lazy" position or side of the tool hereinbefore described.

The fourth or "intermediate" position is indicated in Figure 8 in which the water supply is just opening and the hammer supply through the ports *o* and *p* is preferably about one half or three fourths full on. The oil supply is still closed and the air feeding element through the port *h* is fully open while the air feed bleeder *Q* is also fully open. This "intermediate" position is substantially the same position as indicated in Figure 7 but the hammer is stronger in order to increase the blow and it is to be observed that I am enabled to reach this intermediate position by continuous movement of the throttle handle *T* clockwise in the same direction in which movement has been proceeding.

In the fifth position indicated in Figure 9 the supply of water and oil to the machine and the supply of motive fluid to the percussive and feeding elements are full on and the machine is running with full power, with the air feed bleeder *Q* fully closed.

The sixth position indicated in Figure 10 is reached by rotating the second plug portion *O* of the valve backward counter-clockwise without moving the main plug portion *K*. This is accomplished by rocking the second plug portion *O* on the main plug portion *K* and taking up the lost motion between said two plug portions. This slight angular movement of the second plug portion *O* effects the opening of the air feed bleeder *Q* thus reducing the pressure in the air feed without slowing up the tool.

By continuing to turn the valve handle *T* backward other hammer positions may be obtained with light air feed as will be apparent from the diagrammatic figures and the description heretofore given.

I claim:

1. A rock drill comprising a percussive element and a feeding element, both operated by motive fluid under pressure, a throttle valve for distributing motive fluid to both of said elements and ports and passages in said throttle leading to the percussive and feeding elements for carrying out the following cycle of operations when the valve is moved from closed position:—first, opening an air feed bleeder to prevent pressure from accumulating in the feeding element; secondly, closing the air feed bleeder and slightly opening the supply to the feeding element; thirdly, slightly opening the supply to the percussive element, increasing the supply to the feeding element and slightly opening the air feed bleeder; fourth, increasing the supply to the percussive element,

opening full supply to the feeding element 65 and increasing the air feed bleeder to full opening; fifth, opening the supply to the percussive element and the feeding element to full on position, with the bleeder entirely closed off; sixth, continuing the conditions 70 of the fifth stage with the bleeder full open or varied as desired.

2. A rock drill comprising a percussive element and a feeding element, both operated by motive fluid under pressure, a 75 throttle valve for distributing motive fluid to both of said elements and ports and passages in said throttle leading to the percussive and feeding elements for carrying out the following cycle of operations when the 80 valve is moved from closed position:—first, opening an air feed bleeder to prevent pressure from accumulating in the feeding element; secondly, closing the air feed bleeder and slightly opening the supply to the feeding 85 element, thirdly, slightly opening the supply to the percussive element, increasing the supply to the feeding element and slightly opening the air feed bleeder; fourth, increasing the supply to the percussive element, 90 opening full supply to the feeding element and increasing the air feed bleeder to full opening; fifth, opening the supply to the percussive element and the feeding element to full on position, with the bleeder entirely closed off; sixth, continuing the conditions 95 of the fifth stage with the bleeder full open or varied as desired; and lastly by reversing the movement of the valve at any stage, obtaining any of the combinations 100 mentioned in previous stages up to that point in the cycle, in conjunction with any desired opening of the air feed bleeder.

3. A rock drill comprising a percussive element and a feeding element, both operated 105 by motive fluid under pressure, a two part throttle valve having a lost motion connection between the parts for distributing motive fluid to both of said elements and ports and passages in each part cooperating with 110 ports and passages leading to the percussive and feeding elements for carrying out the following cycle of operations when the valve is moved from closed position:—first, opening an air feed bleeder to prevent pressure from accumulating in the feeding element; secondly, closing the air feed bleeder and slightly opening the supply to the feeding 115 element; thirdly, slightly opening the supply to the percussive element, increasing the supply to the feeding element and slightly opening the air feed bleeder; fourth, increasing the supply to the percussive element, 120 opening full supply to the feeding element and increasing the air feed bleeder to full opening; fifth, opening the supply to the percussive element and the feeding element to full on position, with the bleeder entirely

closed off; sixth, continuing the conditions of the fifth stage with the bleeder full open or varied as desired.

4. A rock drill comprising a percussive element and a feeding element, both operated by motive fluid under pressure, a two part throttle valve having a lost motion connection between the parts for distributing motive fluid to both of said elements and ports and passages in each part cooperating with ports and passages leading to the percussive and feeding elements for carrying out the following cycle of operations when the valve is moved from closed position:—first, opening an air feed bleeder to prevent pressure from accumulating in the feeding element; secondly, closing the air feed bleeder and slightly opening the supply to the feeding element; thirdly, slightly opening the supply to the percussive element, increasing the supply to the feeding element, and slightly opening the air feed bleeder; fourth, increasing the supply to the percussive element, opening full supply to the feeding element and increasing the air feed bleeder to full opening; fifth, opening the supply to the percussive element and the feeding element to full on position, with the bleeder entirely closed off; sixth, continuing the conditions of the fifth stage with the bleeder full open or varied as desired; and lastly, by reversing the movement of one of the said parts of the valve at any stage in the cycle, obtaining any of the combinations mentioned in previous stages up to that point in the cycle in conjunction with any desired opening of the air feed bleeder.

5. A rock drill comprising a percussive element and a feeding element, a throttle for controlling the supply of motive fluid to the percussive element and the feeding element, consisting of a plug portion containing motive fluid supply ports cooperating with ports leading to the said percussive and feeding elements, a second plug portion containing a port open at all times to the atmosphere and capable of being moved into and out of communication with a port leading from the feeding element, a lost motion connection between the said two plug portions of the valve, whereby provision is afforded for varying the amount of motive fluid escaping from the feeding element to the atmosphere without changing the supply of motive fluid to the percussive and feeding elements, and thus varying the force exerted by the feeding element while maintaining any desired supply of motive fluid to the percussive and feeding elements.

6. A rock drill comprising a percussive element and a feeding element, a throttle for controlling the supply of motive fluid to the percussive element and the feeding element, consisting of a plug portion con-

taining motive fluid supply ports cooperating with ports leading to the said percussive and feeding elements, a second plug portion containing a port open at all times to the atmosphere and capable of being moved into and out of communication with a port leading from the feeding element, a lost motion connection between said two plug portions of the valve, whereby provision is afforded for varying the amount of motive fluid escaping from the feeding element to the atmosphere without changing the supply of motive fluid to the percussive and feeding elements, and thus varying the force exerted by the feeding element while maintaining any desired supply of motive fluid to the percussive and feeding elements, and a handle attached to the second plug portion for manually moving the same and for causing movement of the main plug portion when the lost motion between said portions is taken up by the relative movement of the said second plug portion.

7. A rock drill comprising a percussive element and a feeding element, a throttle for controlling the supply of motive fluid to the percussive element and the feeding element, consisting of a plug portion containing motive fluid supply ports cooperating with ports leading to the said percussive and feeding elements, a second plug portion containing a port open at all times to the atmosphere and capable of being moved into and out of communication with a port leading from the feeding element, a lost motion connection between the said two plug portions of the valve, whereby provision is afforded for varying the amount of motive fluid escaping from the feeding element to the atmosphere without changing the supply of motive fluid to the percussive and feeding elements, and thus varying the force exerted by the feeding element while maintaining any desired supply of motive fluid to the percussive and feeding elements, a cam surface on the main plug portion and a water supply valve controlled thereby.

8. A rock drill comprising a percussive element and a feeding element, a throttle for controlling the supply of motive fluid to the percussive element and the feeding element, consisting of a plug portion containing motive fluid supply ports cooperating with ports leading to the said percussive and feeding elements, a second plug portion containing a port open at all times to the atmosphere and capable of being moved into and out of communication with a port leading from the feeding element, a lost motion connection between the said two plug portions of the valve, whereby provision is afforded for varying the amount of motive fluid escaping from the feeding element to the atmosphere without

changing the supply of motive fluid to the percussive and feeding elements, and thus varying the force exerted by the feeding element while maintaining any desired supply of motive fluid to the percussive and feeding elements, a cam surface on the main plug portion and a water supply valve controlled thereby, said cam surface being adapted to open the water supply valve when the motive fluid supply to the percussive element approaches full opening.

In testimony whereof I have signed this specification.

FRED M. SLATER.
